US0D1062435S

(12) **United States Design Patent** (10) **Patent No.:** **US D1,062,435 S**
(45) **Date of Patent:** **** Feb. 18, 2025**

(54) **TOOL FOR INSTALLING SCREEN
PROTECTORS**

(71) Applicant: **Shenzhen Yingeer Technology Co.,
LTD, Shenzhen (CN)**

(72) Inventor: **Zemin Lin, Guangdong (CN)**

(73) Assignee: **Shenzhen Yingeer Technology Co.,
LTD, Shenzhen (CN)**

(**) Term: **15 Years**

(21) Appl. No.: **29/963,137**

(22) Filed: **Sep. 15, 2024**

(51) LOC (15) Cl. **08-05**

(52) U.S. Cl.

USPC **D8/14**

(58) **Field of Classification Search**

(57) **CLAIM**

The ornamental design for a tool for installing screen protectors as shown and described.

DESCRIPTION

FIG. 1 is a front, bottom, and left perspective view of a tool for installing screen protectors showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, top, and right perspective view thereof; and, FIG. 9 is a perspective view thereof, shown with environment.

The broken lines shown in the drawings represent portions of the tool for installing screen protectors that form no part of the claimed design.

1 Claim, 9 Drawing Sheets
